UNITED STATES PATENT OFFICE

JEROME C. BOYLAN, OF CLEVELAND HEIGHTS, OHIO, ASSIGNOR TO THE CLEVELAND CO-OPERATIVE STOVE COMPANY, OF CLEVELAND, OHIO, A CORPORATION OF OHIO

DESIGN FOR A RANGE

Application filed March 7, 1931. Serial No. 38,989. Term of patent 14 years.

To all whom it may concern:

Be it known that I, JEROME C. BOYLAN, a citizen of the United States, and a resident of Cleveland Heights, county of Cuyahoga, and State of Ohio, have invented a new, original, and ornamental Design for Ranges, of which the following is a specification, reference being had to the accompanying drawings, forming a part thereof.

In said annexed drawings:—

Fig. 1 is a perspective view of a range em-

bodying my new design with the burner tops covered; and Fig. 2 is a similar perspective view with the burner tops uncovered.

I claim:—

The ornamental design for a range as shown and described.

Signed by me, this 6th day of March, 1931.

JEROME C. BOYLAN.
